SPRING LOCK

Herbert M. Piker, Hamilton, Ohio, assignor to
The Hamilton Metal Products Company, Ham-
ilton, Ohio, a corporation of Ohio

Application June 21, 1948, Serial No. 34,219

3 Claims. (Cl. 292—86)

1

This invention relates to improvements in a spring lock for use with boxes or the like that have covers hinged thereto for locking the cover in closed position.

Spring locks are not new, per se, but in the past have required a considerable number of parts in order to provide an operative structure or else utilized a portion of the box or its cover as a part of the lock, such for example, supplying the box or the cover with an aperture to receive the keeper of the latch. This construction resulted in wear on the box part which soon became unsightly or the lock as a whole was expensive to produce thereby rendering its use uneconomical in instances where it was desired to produce an inexpensive box.

It is, therefore, the principal object of the present invention to provide a spring lock that is self-contained and adapted to be attached to a box and its cover without utilizing either the box or the cover as a part of the locking mechanism.

Another object of the present invention is the provision of a spring lock which is economical to produce yet sturdy of construction and simple to operate.

A further object of the present invention is the provision of a spring lock that is foolproof in operation, pleasing and artistic in appearance, and of a minimum number of parts consistent with the operation thereof.

Other objects and advantages of the present invention should be readily apparent by reference to the following specification considered in conjunction with the accompanying drawing forming a part thereof and it is to be understood that any modifications may be made in the exact structural details there shown and described, within the scope of the appended claims, without departing from or exceeding the spirit of the invention.

In the drawing:

Fig. 1 is a perspective view of a box having mounted thereon the improved spring lock of the present invention.

Fig. 2 is an enlarged fragmentary vertical sectional view through the lock as seen from line 2—2 on said Fig. 1.

Fig. 3 is a fragmentary elevational view of a part of the box and its cover showing the same having secured thereto the spring lock of the present invention as seen from line 3—3 on Fig. 2.

Fig. 4 is a transverse sectional view through the spring lock of the present invention as seen from line 4—4 on Fig. 2.

2

Fig. 5 is a transverse view through the spring lock taken on a plane above that of Fig. 4 on line 5—5 on Fig. 2.

Fig. 6 is a perspective view of the spring lock of the present invention showing the parts thereof in position before the final locking thereof to one another.

Fig. 7 is a perspective view of the spring catch of the improved spring lock of the present invention.

Fig. 8 is a fragmentary sectional view of a portion of the lock showing a modification in the construction thereof.

Throughout the several views of the drawing similar reference characters are employed to denote the same or similar parts.

As illustrated in Fig. 1 the improved spring lock of the present invention, indicated in general by the reference numeral 10, is attached to a box or container comprising a box proper 11 and a cover 12. The box 11 includes a front 13 and a back to which is hingedly connected the cover 12. The cover 12 has a top 14 from the edge of which depends a flange 15 adapted to embrace an upstanding lip portion 16 from the box front 13 and box back and sides. At the upper end of the box front 11 as well as at the upper ends of its back and sides there is provided a bead 17 which constitutes an abutment for the lower edge of the box cover flange 15.

In order to transport the box the cover top 14 has secured thereto a suitable handle 18 which when not in use is adapted to lie on the upper surface of the cover top 14 and preferably adapted to be disposed within a recess 19 formed in the said cover top 14.

The spring lock 10 comprises a base plate 20 to which is secured a housing 21. The housing 21 has a front 22 from the edges of which project a housing top 23, a housing bottom 24 and housing sides 25 and 26 with the ends of said top, bottom and sides free. The housing 21 is of less width than the base plate 20 and has projecting from the sides 25 and 26, respectively, ears 27 and 28

which are, respectively, adapted to pass through elongated apertures 29 in the base plate 20, and whereby the said housing 21 is secured to the base plate 20 by having said ears bent to engage the back surface of the base plate 20 and effect a clamping of the housing 21 in position between the said ears 27 and 28 and the free edges of the housing top, bottom and sides.

Disposed within the housing 21 is a spring latch, indicated in general by the reference numeral 30, which comprises a foot member 31,

3

a central or body portion 32 and an inclined flexing connecting portion 33 extending between the upper end of the foot portion 31 and the lower end of the body portion 32. The upper end of the spring latch body portion 32 is upwardly and inwardly inclined as at 34 providing a latch finger. Within the latch finger 34 and upper end of the latch body portion 32 is formed an aperture 35 thereby providing a latching bar 36 at the outer end of the latch finger portion 34.

The spring latch foot 31 is provided with apertures 37 adapted to be aligned with similar apertures in the lower end of the base plate 20 and through which aligned apertures extend rivets 38 whereby the spring latch 30 is secured to the base plate 20. It should be noted that the spring latch 30 is adapted to be positioned substantially centrally, laterally, of the housing 21 and base plate 20. When the spring latch 30 is in operative position relative to the housing 21 and the base plate 20 the latch finger 34 is positioned beneath the lock housing top 23 in reasonably close proximity thereto and the said lock housing top 23 is provided with an aperture 39 in alignment with the spring finger aperture 35. It is by way of the lock housing top aperture 39 that locking or latching engagement is obtained with the spring finger 34 and its latching bar 36.

In order to actuate the spring latch 30, particularly to unlock the same, the said spring latch body portion 32 has secured thereto and projecting therefrom a thumb or finger piece 40 which is illustrated as substantially button shape in appearance. The thumb or finger piece 40 is secured, to the latch body portion 32 by any suitable means, such for example as by a rivet 41. The thumb or finger piece 40 is adapted to project forwardly of the lock housing front 22 and for which purpose the said lock housing front 22 is provided with an aperture 42 slightly larger in diameter than the thumb or finger piece 40 so as to offer no interference with said thumb or finger piece during its operation. As shown in Fig. 2 the upper inner end of the latch finger 34 and its latching bar 36 are normally spaced forwardly of the base plate 20 so that the said spring latch 30 may be rearwardly flexed.

The lock base plate 20 with its housing 21 is adapted to be secured to the box front 13 for which purpose the base plate 21 has projecting respectively, from its vertical sides bendable fastening ears 43 and 44 each adapted to pass through an aperture 45 in the said box front 13. The securing of the base plate 20 to the box front 13 is obvious since up-setting or bending of the ears 43 and 44 against the inner surface of the box front 13 will effectively clamp the said box front between the base plate 20 and said ears 43 and 44. The spring lock base plate and its housing 21 are located on the box front to have the upper edges thereof substantially aligned with the head 17 or at the bottom edge of the cover depending flange 15.

Secured to the lid or cover flange 15 is the spring lock keeper which conveniently is made as a stamping to provide an upstanding or outwardly projecting portion or body member 46 that has an effective depth substantially equal to the depth of the housing 21 and its base plate 20. The outwardly projecting portion 46 is provided with rearwardly extending sides 47 each of which has at its base laterally projecting wings 48 and 49 which simulate the extension of the base plate 20 beyond the housing 21. The keeper or catch is adapted to be secured to the lid or

4

cover flange 15 just above the base plate 20 and housing 21 and for this purpose has projecting from the vertical edges of the wings 48 and 49 bendable ears 50 and in addition has projecting from its upper edge a bendable ear 51 and each of which ears 50 and 51 is adapted to pass through an aperture 52 formed in the lid or cover flange 15 to be upset or bent in effecting the securing of the keeper or catch to the cover.

Projecting from the lower edge of the keeper or catch body portion 46 is the keeper proper or lug 53 that has the sides thereof bent normal thereto as at 54 and 55 thereby giving the lug 53 a substantially U-shape in cross section. Each of the lug sides 54 and 55 is provided with a V-shaped cut therein to provide a tooth 56 at a point intermediate the vertical height of the lug 53. The teeth 56 are adapted to underlie the spring latch latching bar 36. Each of the lug sides 54 and 55 below its tooth 56 is provided with an inclined portion 57 which acts as a cam in flexing the spring latch 30 during the time of projecting the teeth 56 beneath the said latching bar 36.

From the foregoing description and the drawing, particularly Fig. 2, it is believed that the operation of the spring lock of the present invention is well understood. Briefly, however, with the spring lock parts in the position of Fig. 6 continued downward movement of the cover 12 will cause the keeper or catch lug 53 to pass through the lock housing top aperture 39 into the spring latch finger aperture 35. The cam faces 57 on the keeper or catch lug sides 54 and 55 will engage the latch bar 36 and rearwardly, as seen in Fig. 2, flex the spring latch 30 until the teeth or seats 56 on said keeper or catch lug sides 54 and 55 are beneath the spring latching bar 36 whereupon the said spring latch 30 will be released to dispose the latching bar 36 above the said teeth or seats 56 and thereby prevent raising of the cover or lid 12 of the box. When it is desired to open the cover or lid 12 the operator need merely engage the thumb or finger piece 40 and rearwardly press the same to thereby again free the spring latch 30 by removing the latching bar 36 from the seats or teeth 56 and permit the withdrawal of the keeper or catch lug 53 from the opening 39.

The construction set forth in the foregoing description utilized a base plate 20 which secured the housing 21 to the box and at the same time provided a mounting plate for the spring latch 30. In the modification illustrated in Fig. 8 the base plate 20 has been eliminated and the bottom 24 of the housing 21 is provided with an extension which is upwardly disposed to be parallel with the housing front 22 and which portion is indicated in Fig. 8 by the reference numeral 58. This upward extension need be no higher than the foot portion 31 of the spring latch 30 and is provided with apertures to be aligned with the apertures 37 in the spring latch foot portion 31 and through these aligned apertures pass the rivets 38 for thereby securing the said spring latch 30 directly to the lock housing 21. In order to secure the lock housing 21 to the box front 13 the ears 27 and 28 thereof are passed directly through apertures in the housing front 13.

From the foregoing it is believed obvious that there has been provided an improved spring lock for boxes and the like which answers the objects initially set forth.

What is claimed is:

1. In a spring lock including a catch having a latching shoulder intermediate its ends and an actuating cam terminating at the shoulder, the combination of a lock housing comprising an outwardly spaced front and an apertured top, a spring latch within said housing having the body portion thereof adjacent the housing front and mounted at its lower end for flexing movement inwardly of said housing front, the spring latch having its upper end portion upwardly and inwardly inclined with an aperture in said inwardly inclined portion forming a latching bar at the upper end of the latch to be below the housing top and extend laterally of the top opening, said latch aperture being aligned with the housing top aperture through which aligned apertures the catch passes to have the actuating cam thereof engage the latching bar for inwardly flexing the spring latch until its latching bar is above and on the catch shoulder, and a finger piece carried by the spring latch intermediate its ends projecting through the latch housing front for manual engagement for inwardly flexing the spring latch to disengage its latching bar from the catch shoulder.

2. In a spring lock including a catch having a latching shoulder intermediate its ends and an actuating cam terminating at the shoulder, the combination of a lock housing having a front and rearwardly projecting top, bottom and sides, a base plate secured to the free ends of the lock housing top, bottom and sides, said lock housing top having an aperture therethrough, a spring latch within the lock housing having a body portion adjacent the inner surface of the lock housing front and having its lower end secured to the base plate in such manner that the spring latch body portion may be flexed toward the base plate, said spring latch having its upper end portion upwardly and inwardly inclined and provided with an aperture to provide in said upwardly and inwardly inclined portion a latching bar at the upper end of the spring latch to be below the housing top and extend laterally of the top opening, said latch aperture and lock housing top aperture being aligned to permit the passage therethrough of the catch and engagement of the latch latching bar by the catch actuating cam for inwardly flexing the latch until said

50

latching bar is above and seated on the catch shoulder, and means operable exteriorly of the lock housing for inwardly flexing the latch for releasing the latching bar from the catch shoulder.

3. In a spring lock including a catch having a latching shoulder intermediate its ends and an actuating cam terminating at the shoulder, the combination of a lock housing having a front and rearwardly projecting top, bottom and sides, a base plate secured to the free ends of the lock housing top, bottom and sides, said lock housing top having an aperture therethrough, a spring latch within the lock housing having a body portion adjacent the inner surface of the lock housing and having its lower end secured to the base plate in such manner that the spring latch body portion may be flexed toward the base plate, said spring latch having its upper end portion upwardly and inwardly inclined and provided in said upwardly and inwardly inclined portion with an aperture to provide a latching bar at the upper end of the spring latch to be below the housing top and extend laterally of the top opening, said latch aperture and lock housing top aperture being aligned to permit the passage therethrough of the catch and engagement of the latch latching bar by the catch actuating cam for inwardly flexing the latch until said latching bar is above and seated on the catch shoulder, and means operable from the exterior of the lock housing for inwardly flexing the latch for releasing the latching bar from the catch shoulder, comprising a finger piece carried by the spring latch intermediate the ends of its body portion and projecting through an aperture in the lock housing.

HERBERT M. PIKER.
